APPARATUS FOR FOCUSING HIGH-ENERGY PARTICLES

Wolfgang K. H. Panofsky and William R. Baker,
Alameda, Calif., assignors to the United States
of America as represented by the United States
Atomic Energy Commission

Application March 15, 1950, Serial No. 149,812

6 Claims. (Cl. 315—237)

1

This invention relates to a magnetic arc lens and more particularly to an apparatus for focusing high energy particles utilizing the magnetic field surrounding an electric arc discharge.

In recent years great strides have been made in developing accelerators for charged particles such as cyclotrons, betatrons, synchrotrons, linear accelerators, and Van de Graaff generators. Such known accelerators have inherent characteristics which prevent the production of beams of high energy particles having a high intensity over a small cross-sectional area. Since a majority of the work which it is desired to accomplish with accelerators of the above-mentioned type require beam density rather than total current, a focusing device is desirable for use therewith.

It has been found that the desired focusing of a beam of high energy particles is possible by utilizing magnets along the path of the beam; however, the use of such magnets, while practical in principle, involves the use of magnets having a large physical size and of severe modifications in the structure of the accelerator. The present invention overcomes such difficulties by providing a simple current carrying cylindrical conductor which is transparent to the passage of a beam and which is disposed with its axis parallel to the beam. The magnetic field set-up by the current flowing through the conductor establishes a focusing force upon the particles of the beam. It will be readily apparent that such a device may be easily installed with minor modifications to the accelerator itself.

It is therefore an object of the present invention to provide a new and improved method and apparatus for focusing high energy particles in a beam.

Another object of the present invention is to provide a magnetic arc lens for focusing high energy particles in a beam.

Still another object of the present invention is to provide a current carrying conductor which is cylindrical in form and transparent to a high energy particle beam to accomplish focusing thereof.

A further object of the present invention is to provide a focusing device utilizing the magnetic field of a cylindrical current carrying conductor to focus a beam of high energy particles.

Another important object of the present invention is to provide an arc discharge between electrodes which are substantially transparent to a particle beam whereby the arc discharge establishes a magnetic field having a focusing effect upon such beam.

2

An additional object of the present invention is to provide an arc discharge between electrodes which are substantially transparent to a high energy particle beam and an electrical circuit for establishing the arc discharge.

Still another object of the present invention is to provide a magnetic arc lens which is readily adaptable for use with particle accelerators and which requires a minimum of modification to install.

Further objects and advantages will be apparent in the following description and claims considered together with the accompanying drawing in which:

15 Figure 1 is a diagrammatic representation of a cylindrical current carrying conductor in section;

Fig. 2 is a diagrammatic end view of the cylindrical current carrying conductor of Fig. 1; and

20 Fig. 3 is a longitudinal section of the present invention and includes a schematic wiring diagram of a preferred form of electrical connections therefor.

Referring to the drawing in detail, and to Figs. 25 1 and 2 in particular, a hollow cylindrical current carrying conductor 11 having a length L and a diameter 2a is disposed in the path of and parallel to a high energy particle beam 12. Flowing through the conductor 11 is a uniform arc discharge 13 which establishes a magnetic field as indicated by concentric circles 14 in Fig. 2. With such conditions existing the radial variation of the magnetic field will be found as represented by the curve 16 and the direction of the forces 30 acting upon particles of the beam because of the field are inward, as shown by arrows 17. The effect of the forces due to the magnetic field upon the beam 12 is shown in Fig. 1 to be toward the center or zero magnetic field. It is thus apparent that the magnetic field caused by the 35 uniform current density of the arc increases linearly with the radius, and a linear restoring force on the beam results. It can easily be shown that if such a device is effectively a "thin" lens, it will give rise to a focal length

40

$$F = \frac{a}{L} \frac{(BP)}{B_0}$$

45 where (BP) is the momentum of the beam, B_0 is the magnetic induction at the outer edge of the conductor, and a and L are dimensions as defined in Fig. 1.

50 Referring now to Fig. 3, a cylindrical tube 21, preferably formed of a non-conducting material 55 such as glass, serves as an envelope. Each end

of the tube 21 has an outwardly beveled portion 22 to receive a clamping ring 23 having an oppositely beveled opening 24 therein. To provide an electrode 26 at each end of the tube 21, a hollow metallic cylinder 27, preferably made of aluminum, is fitted thereto by means of an axially extending portion 28 having an outside diameter substantially equal to the inside diameter of the tube 21. An outwardly extending flange 29 is provided on the electrodes 26 and is utilized for suitably securing each of the electrodes to the respective clamping ring 23 as by bolts 31. Preferably a sealing gasket 32 of rubber, or other suitable non-conducting material, is disposed between the end of the tube 21 and the flange 29 to ensure an air-tight connection. Each of the electrodes 26 is provided with an aperture 33, one for suitable connection to a source (not shown) of gas, such as hydrogen, and the other for suitable connection to a vacuum pump (not shown). The outermost end of each of the electrodes is closed by a metallic foil 36, chosen to be substantially transparent to the beam which it is desired to focus. Such foil 36 is suitably secured to a retaining ring 37 which in turn is fastened to the electrode 26 by means of bolts 38. To provide an air-tight connection between the ring 37 and the electrode 26, a sealing gasket 39 is disposed therebetween.

One of the electrodes 26 is electrically connected to a ground connection 50 by a lead 51. The other electrode 26 is connected to one sphere 52 of a sphere gap 53. The other sphere 54 of the sphere gap 53 is connected to the ground connection 50 through a storage condenser 56. To charge the condenser 56 a conventional power supply 57 is connected across the condenser with a current limiting resistor 58 between the power supply and the junction between the sphere 54 and condenser 56.

A further connection is made from the junction of the electrode 26 and the sphere 52 to a parallel circuit, comprising a resistor 61 and condenser 62, which is connected to the ground connection 50 through the secondary winding 63 of a pulse transformer 64. One side of the primary winding 66 of the transformer 64 is connected to the ground connection 50 and the other side is connected to the anode of a tube 67 through a condenser 68. Also connected to the anode of the tube 67 is one side of a current limiting resistor 69, the other side of which is connected to a terminal 71 of a conventional power supply 72. A terminal 73 of the power supply 72 is connected to the ground connection 50. The cathode of the tube 67 is directly connected to the ground connection 50. The control grid of the tube 67 is connected to the ground connection 50 through a resistor 74 and to one terminal 75 of a conventional pulse generator 77 through a coupling condenser 78. The other terminal 79 of the generator 77 is connected to the ground connection 50.

Consider now the operation of the present invention with the current carrying conductor assembled and the electrical connections thereto accomplished in the foregoing described manner. First, the vacuum pump is used to exhaust the air from the current carrying conductor and then hydrogen is introduced to a pressure of .3 to .5 mm. as a suitable medium for an arc discharge.

The condenser 56 is charged by the power supply 57; however, the value of the voltage is insufficient to cause a break down in the gap between the spheres 52 and 54. Because of the

foregoing, and to control the discharge of the condenser 56, it is necessary to apply a trigger voltage and this is accomplished by the remainder of the electrical circuit shown on Fig. 3. With the occurrence of a positive pulse of voltage at the output of the generator 77, the tube 67 conducts and discharges the condenser 68, which has been previously charged by the power supply 72. The discharge of the condenser 68 results in a surge of current through the primary winding 66 of the pulse transformer 64. Since the pulse transformer 64 is a step-up transformer, the secondary winding 63 develops a high value voltage pulse which is applied across the sphere gap 53 and the condenser 56 through the condenser 62 and resistor 61 combination. Such a pulse of voltage causes a breakdown in the gap between the spheres 52 and 54 and results in the condenser 56 discharging through an arc established between the electrodes 26.

With the arc established, it will be readily apparent that a magnetic field, similar to that illustrated in Figs. 1 and 2, is established. Therefore a beam of high energy particles directed through the arc in the same direction will undergo forces which focus such beam.

It has been found that a synchro-cyclotron proton beam having an energy as high as 350 Mev may be easily and effectively focused with the present invention. The retaining ring 37, to which the sphere gap 53 is connected, was sealed over an aperture in the vacuum tank of the synchro-cyclotron at the point of beam emergence. The entrance foil 36 was made of 1½ mil dural foil and was found to produce no appreciable broadening of the beam by multiple scattering in the foil, even at the higher energies. It was possible to use such a thin entrance foil because of the slight variation in pressure on either side. As stated previously hydrogen at a pressure of .3 to .5 mm. is a suitable medium for the arc discharge and was maintained during operation. It was found advisable to circulate the hydrogen continuously to purify the gas from gases generated from the surfaces of the electrodes. The exit foil 36 at the other retaining ring was made of somewhat thicker material, approximately .010 in. of aluminum, to withstand the difference in pressure involved and any scattering effect may be minimized by placing the target close thereto.

The arc was fed from the condenser 56 through the sphere gap 53 triggered by a 70 kv. pulse transformer. The arc was operated at a pulse repetition rate of approximately 60 per second, in synchronism with the cycle of the synchro-cyclotron, by initiating operation of the pulse generator 77 each time the electrostatic deflector of the cyclotron was operated to bring the beam out. Under these conditions the arc operated with a current of 4000 amperes and an arc drop of .9 kv. This magnetic arc lens installation, described as an illustration, focused the diverging beam into a well defined beam having a considerably smaller cross section and a much higher density.

From the foregoing it will be readily apparent that such an arrangement could be easily utilized to bend a beam of high energy particles by forming an arc discharge through a tube which is bent in any predetermined manner. In such instance the forces of the magnetic field established by the arc would force the beam to follow the arc.

While the salient features of the present invention have been described with respect to one

embodiment it will, of course, be apparent that numerous modifications and changes may be made within the spirit and scope of the invention and it is therefore not desired to limit the invention to the exact details shown except insofar as they may be defined in the following claims.

What is claimed is:

1. A magnetic arc lens adapted to be disposed in the path of and parallel to a beam of high energy particles, comprising an envelope defining a chamber, a pair of tubular electrodes disposed one at each end of said envelope, sealing means substantially transparent to said beam mounted across the outer opening of said electrodes, means for maintaining a gas medium in said chamber, and electrical means connected to said electrodes for establishing an arc between said electrodes in the direction of said beam whereby the magnetic field of said arc exerts a focusing force upon particles of said beam.

2. A magnetic arc lens adapted to be disposed in the path of and parallel to a beam of high energy particles, comprising a tubular envelope defining a chamber, a pair of tubular electrodes having a cross section substantially the same as said envelope and being disposed one at each end of said envelope, sealing means substantially transparent to said beam mounted across the outer opening of said electrodes, means for evacuating said chamber, means for introducing a gas medium into said evacuated chamber, and electrical means connected to said electrodes for establishing an arc therebetween in the direction of travel of said beam whereby the magnetic field of said arc exerts a focusing force upon particles of said beam.

3. A magnetic arc lens adapted to be disposed in the path of and parallel to a beam of high energy particles, comprising an elongated glass tube defining a chamber, a pair of metallic tubular electrodes having a cross section substantially the same as said envelope and being mounted one at each end of said envelope, metallic foils substantially transparent to said beam mounted across the outer opening of said electrodes, means for evacuating said chamber, means for introducing a gas medium into said evacuated chamber, and electrical means connected to said electrodes for establishing an arc therebetween in the direction of travel of said beam whereby the magnetic field of said arc exerts a focusing force upon particles of said beam.

4. A magnetic arc lens adapted to be disposed in the path of and parallel to a beam of high energy particles, comprising an envelope defining a chamber, a pair of tubular electrodes disposed one at each end of said envelope, sealing means substantially transparent to said beam mounted over the outer opening of said electrodes, means for maintaining a gas medium in said chamber, a sphere gap and a condenser serially connected between one of said electrodes and a ground connection, the other of said electrodes being con-

nected to said ground connection, means connected across said condenser for charging said condenser to a voltage less than the breakdown voltage of said sphere gap and the gap between said electrodes, and means connected across said sphere gap and condenser for applying a pulse of voltage to cause a breakdown of said sphere gap and discharge said condenser through an arc established in the direction of said beam between said electrodes, whereby the magnetic field of said arc exerts a focusing force upon particles of said beam.

5. A magnetic arc lens adapted to be disposed in the path of and parallel to a beam of high energy particles, comprising an envelope defining a chamber, a pair of tubular electrodes disposed one at each end of said envelope, sealing means substantially transparent to said beam mounted over the outer opening of said electrodes, means for maintaining a gas medium in said chamber, a sphere gap connected to one of said electrodes, the other of said electrodes being connected to a ground connection, a storage condenser connected between said sphere gap and said ground connection, a power supply connected across said storage condenser for charging said condenser to a voltage less than the breakdown voltage of said sphere gap and the gap between said electrodes, the secondary winding of a pulse transformer connected across said sphere gap and storage condenser through a coupling condenser, and means connected to the primary winding of said pulse transformer for applying a pulse of voltage thereacross, whereby an arc is established between said electrodes to develop a magnetic field having a focusing action on particles of said beam.

6. In a device for focusing charged particles, the combination comprising a tubular discharge chamber having a first particle transparent electrode and a similar second electrode spaced therefrom, said first electrode being connected to ground, a spark gap having one side connected to said second electrode, a condenser connected between the other side of said spark gap and ground, means for charging said condenser, and connected to said spark gap means for triggering said spark gap whereby said capacitor is discharged through said tubular discharge chamber.
